CLAIM

The ornamental design for a hydraulic torque wrench as shown and described.

DESCRIPTION

1.1 : Perspective**1.2** : Perspective**1.3** : Top**1.4** : Right**1.5** : Front**1.6** : Left**1.7** : Back**1.8** : Bottom

The design resides in the shape and configuration of the article as shown in the drawings; no protection is sought for the matter shown in dotted lines.
